(57) **CLAIM**

The ornamental design for an egg holder, as shown and described.

DESCRIPTION

FIG. 1 is a top perspective view of an egg holder showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view thereof;

FIG. 9 is a perspective view showing the egg holder in a stacked arrangement;

FIG. 10 is a top perspective view of the egg holder in a disassembled state; and,

FIG. 11 is a bottom perspective view thereof.

Broken lines in the drawings depict portions of the egg holder that form no part of the claimed design.
